UNITED STATES PATENT OFFICE.

JOSEPH OPPMAN, OF CONNELLSVILLE, PENNSYLVANIA, ASSIGNOR OF ONE-HALF TO
PETER MIKALARIAS, OF CONNELLSVILLE, PENNSYLVANIA.

PAPER PASTING AND SEVERING MACHINE.

Application filed February 10, 1922. Serial No. 535,597.

To all whom it may concern:

Be it known that I, JOSEPH OPPMAN, a citizen of the United States, residing at Connellsburg, in the county of Fayette and State 5 of Pennsylvania, have invented certain new and useful Improvements in Paper Pasting and Severing Machines, of which the following is a specification.

This invention relates to apparatus for applying paste to webs or rolls of paper, dividing the pasted webs into strips of any required width, and severing the pasted and divided strips into predetermined lengths, and has for one of its objects to simplify and improve 10 the construction and increase the efficiency and utility of devices of this character.

Another object of the invention is to provide a device of this character which may 20 be adapted to webs or rolls of paper of varying widths and lengths, and to apply paste uniformly to the whole web and divide the same into strips of varying widths, and severing the pasted and divided strips into predetermined 25 lengths.

With these and other objects in view, the invention consists in certain novel features of construction as hereinafter shown and described and then specifically pointed out in 30 the claims and in the drawings illustrative of the preferred embodiment of the invention;

Figure 1 is an end elevation, and

Fig. 2 is a plan view of the improved apparatus.

Fig. 3 is an enlarged sectional detail on the line 3-3 of Fig. 1.

Fig. 4 is a front view of the parts shown in Fig. 3.

Fig. 5 is a section on the line 5-5 of 40 Fig. 3.

Fig. 6 is an enlarged section on the line 6-6 of Fig. 1.

Fig. 7 is an enlarged section on the line 7-7 of Fig. 1.

Fig. 8 is an enlarged section on the line 45 8-8 of Fig. 1.

Fig. 9 is an enlarged sectional detail of the transverse severing blades.

The improved apparatus is designed 50 more particularly for applying paste to a web or roll of paper, for instance wall paper, dividing the pasted web in strips of predetermined widths and severing the pasted and divided strips in predetermined lengths.

55 The improved apparatus comprises a sup-

porting structure including end members 10, of relatively heavy material, preferably of wood. Supported between the end members 10 is a trough member, preferably of sheet metal and indicated at 11 having one side about in line with the center of the trough as indicated at 12 and the other side extending upwardly as indicated at 13.

Extending between the end members 10 is an L-shaped member indicated at 14, preferably of sheet metal, and coacting with the upwardly extending side 13 of the trough to form a tank or reservoir for paste.

The side 13 of the trough also forms one wall of the tank, the latter underlying a portion of the trough as indicated at 15.

A stay member 16 is disposed beneath the trough to support the same.

Mounted for rotation in the trough 11 is a drum comprising a cylindrical body portion 17 and closed ends, one of which is indicated at 18 in Fig. 1, and disposed in the end members 10 are pins, one of which is indicated at 19.

By this means the drum is mounted for rotation on the end members 11 and is therefore rotative in the trough. The "barrel" or body 17 of the drum is concentric to the curved portion of the trough and only slightly smaller than the same, so that a thin film of the paste will flow into this thin space and be spread uniformly over the barrel of the drum as the latter is rotated, as hereafter explained.

Extending between the end members 10 is a guide roller 20 having journals, one of which is indicated at 21 and including a threaded end 22 engaging in the roller 20. The body of each of the pins 21 engages in a wear sleeve, one of which is represented at 23, in Fig. 3, in the end members 10.

One of the pins 21 is provided with a friction disk 24 operating externally of the adjacent end member 10, as shown.

The roller 20 is preferably located above the center of the drum 17, as shown in Figs. 1 and 2.

Formed in the inner or confronting faces of the end members 10 are vertical guideways 25 to receive the journals 26 of a bearing roller 27.

Formed in the confronting faces of the end members 10 are horizontal guideways 28 to receive the ends of a rod 29 designed to support a roll of paper indicated at 30,

the rod being retained in place by hooks 29.

The end of the web of paper 31 is passed between the barrel 17 of the drum and the bearing roller 27 and thence between the barrel 17 of the drum and the guide roller 20 and thence drawn upwardly, the pulling upwardly of the web of paper causing the drum to be rotated and carry a thin film of paste with it and apply it uniformly upon the paper as it is drawn over the drum and held in contact therewith by the gravity of the bearing roller 27.

By this means the requisite amount of paste is uniformly and evenly applied to the paper as it is drawn upwardly, and the paper held in contact with the drum by the weight of the bearing roller with sufficient tension to insure the proper action.

Bearing upon each of the end members 10 is a support 32 having shoulders 33 at the ends and a flat uniform face 34 between the shoulders. Bearing over each of the members 32 is a holding member 35 having down-turned ends engaging the shoulders 33, the intermediate portions of the member 32 co-acting to form guideways having parallel confronting faces. At one end of each of the members 32, the shoulders 33 are extended inwardly to form seats for a severing blade 37 and its backing member 38. The blade 37 is provided with a plurality of transverse slots 39 to receive clamp screws 40, to enable the blade to be adjusted relative to its backing member 38. Slidably disposed at its ends in the guideways formed by the coating members 32 and 35, is a backing member 41 of another blade 42 having transverse slots indicated at 43 to receive clamp screws 44, and providing means for the adjustment of the blade 42 relative to the backing member 41 and the stationary blade 37.

The members 35 are provided respectively with longitudinal slots 45, and rising from the member 41 and extending through the slots are studs 46, and rising respectively from the members 35 at the end nearest to the stationary blade 37 are studs 47, and connecting the studs 46 and 47 at each side of the device is a pull string 48.

The springs 48 operate to draw the movable blade 42 and its backing member 41 toward the stationary blade and cause the blades to coat as hereafter explained.

Rising from the members 35 near the stationary blade, are bearings 49 in which the journals of a guide roller 50 are rotatably mounted, and rising from the members 35 intermediate their ends, are bearings 51 to support a rod 52.

Slidably on the rod 52 is a hanger device 53 carrying a cutting wheel 54 coacting with the roller 50 to divide the web 31 of paper as the latter is drawn upwardly.

Attached by screws or other fastening

devices 55 at one of the end members 10, is a bracket device 56 having a longitudinally slotted arm 57 extending therefrom and in parallel relation to and spaced from the friction disk 24.

Slidable in the slot of the arm 57 is a forked member 58; the latter adjustably supported relative to the arm 57 by a clamp screw 59.

Extending from the outer end of the slotted arm 57 and toward the disk 24, are spaced guide members 60 between which a bearing block 61 is slidably disposed, and yieldably supported by a spring 62.

A rod 61' extends from the block 61, and extends through the adjacent portion of the arm 57 and is threaded to receive a milled nut 61''. The spring 62 operates to maintain the friction pinion 65 yieldably in engagement with the friction disk 24.

Attached to the same end member 10 which carries the bracket 56 is another bracket 63, and journaled at its ends respectively in the bracket 63 and block 61 is a shaft 64, the latter passing through the bracket 58 and supporting a friction pinion 65 which coacts with the friction disk 24.

The pinion 65 is held from lateral movement by the sides of the bracket 58, but is slidable on the shaft through the coaction of a feather key, represented at 66.

The bracket 58 is adjustable in the slot of the member 57 and held in adjusted position to locate the pinion 65 nearer to or farther from the center of the disk 24, to control the speed imparted to the pinion and thence to the shaft 64, as will be obvious.

Attached to the adjacent end member 10 is a bracket 67 carrying a stud 68 upon which a worm gear 69 is mounted to rotate, and coacts with a worm pinion 70 on the shaft 64.

Attached by clamp screws 71 to the worm gear 69 is a slotted trip arm 72 having one extended end 73.

The worm gear 69 is provided with slots 74 where the clamp screws 71 pass, so that the members 72 may be adjusted to control the distance which the terminal 73 projects beyond the gear 69.

At its ends the base member 41 of the cutting blade 42 extends beyond the member 32 and the end members 10, and the extended portions each provided with a socket or notch indicated at 76.

Extending through the members 32 and projecting at the ends beyond the same is a rock shaft 77 having spring controlled pawls 78 at the ends to engage in the sockets 76, the pawl which is adjacent to the worm gear 69 and its arm 72 having another arm 79 extending into the path of the extended terminal 73 of the arm 72.

The member 41 is provided with a pull handle 80 by which it may be manually drawn outwardly against the resistance of

the springs 48, to cause the sockets 76 to be engaged by the pawls 78, and thus hold the member 41 and its blade 42 yieldably in withdrawn position, as shown in Fig. 1.

5 If it is desired to dispense with the operation of the severing blades 37 and 42, the block 61 and shaft 64 may be moved outwardly by rotating the nut 61² against the resistance of the spring 62 until the pinion 10 65 is disengaged from the wheel 24.

With an apparatus thus described, the operation is as follows:

A roll of paper to be treated, for instance a roll of wall paper with the edges untrimmed, is disposed on the rod 29 and the free end passed over the drum 17 beneath the rollers 27 and 20 and over the roller 50, the bracket 53 having been previously released by loosening the clamp nut 81 by 20 which the cutter 54 is held in inoperative position and turned back out of the way.

The bracket 53 is then returned to operative position with its cutting wheel in engagement with the paper as it passes over 25 the roller 50.

The valve, not shown, which controls the flow of paste from the tank is then opened, and as the paper 31 is drawn upward, the drum 17 is rotated by the friction of the 30 paper and carries a thin film of paste with it and applies it uniformly to the paper as it passes between and over the several rollers, the cutting wheel 54 at the same time dividing the web of paper longitudinally.

When employed for pasting and trimming wall paper, the bracket 53 will be adjusted to cut the unprinted edge from the paper, and if both edges are to be trimmed, 40 two of the brackets with the cutting blades will be employed, as is obvious.

As the pasted and divided web is drawn upwardly it imparts motion to the roller 20 and thence to the friction disk 24, the 45 friction pinion 65, the shaft 64, worm pinion 70, worm gear 69 and its arms 72.

By adjusting the friction pinion 65 in the slot or guideway in the member 57, the speed may be readily controlled to correspondingly control the movements of the 50 arm 72 and cause the extension 73 of the latter to trip the pawls 78, 79 once during each revolution of the wheel 69 and thus release the member 41 and its blade 42 and permit 55 the springs 48 to move the blade against the pasted and divided paper and coat with the blade 37 to sever it transversely.

The speed of the wheel 69 may thus be controlled to correspondingly control the 60 length of the paper which is drawn upwardly above the severing knife 37, and

when this length is reached, the member 72 will release the movable blade, as before described.

The upper face of the member 57 is provided with graduations, indicated at 82, to enable the pinion 65 to be accurately set, to correspond to the required lengths of the webs or strips.

The preferred embodiment of the invention is disclosed in the drawings and set forth in the specification, but it will be understood that modifications within the scope of the claimed invention may be made in the construction without departing from the principle of the invention or sacrificing any of its advantages.

Having thus described the invention, what is claimed as new is:—

1. In an apparatus of the class described, 80 a roller over which a web of paper is adapted to be drawn and thereby rotating the roller, a friction disk rotative with said roller, a shaft mounted for rotation, a friction pinion engaging said disk and rotative 85 with said shaft and slidably on the same, means for adjusting said pinion longitudinally of the shaft to control the speed, a worm gear, a worm pinion carried by said shaft and engaging said gear, a stationary 90 severing blade, a movable severing blade, yieldable means for moving the movable severing blade into operative position, pawl devices engaging said movable severing blade and holding the same in inoperative 95 position against the resistance of the yieldable means, and means carried by the worm gear whereby the pawl devices are released at each revolution of the worm gear.

2. In an apparatus of the class described, 100 a roller beneath which a web of paper is adapted to be drawn and thereby rotating the roller, a friction disk rotative with said roller, a shaft mounted for rotation, a friction pinion engaging said disk and rotative 105 with said shaft and slidably on the same, means for adjusting said pinion longitudinally of the shaft to control the speed, a worm gear, a worm pinion carried by said shaft and engaging said gear, a trip arm carried by said worm gear, yieldable means for moving the movable severing blade into operative position, and pawl devices engaging said movable severing blade and the same in 110 inoperative position against the resistance of the yieldable means, one of said pawl devices extending into the path of the trip arm and adapted to be actuated at each revolution of the worm gear.

In testimony whereof, I affix my signature hereto.

JOSEPH OPPMAN.
